Inventor

Willis Straw

UNITED STATES PATENT OFFICE.

WILLIS STRAW, OF DALTON, NEW HAMPSHIRE.

CHAIN-HOOK.

Specification of Letters Patent No. 11,306, dated July 11, 1854.

To all whom it may concern:

Be it known that I, WILLIS STRAW, of Dalton, in the county of Coos and State of New Hampshire, have invented a new and Improved Chain-Hook; and I do hereby declare that the following is a full and exact description of the same, reference being had to the accompanying drawings and to the letters of reference marked thereon.

10 The nature of my invention consists in attaching to a chain hook of ordinary shape (see letter A on the drawings) at the "eye" end of the same (see letter B) by means of a toggle joint and rivet (and for certain 15 uses, a screw) (see C and D) an "iron guard," (see letter F,) one end of which (see letter E) is attached to the chain by

means of the link passing through an "eye" in the end of the guard (see letter G) and the other end of the "guard" having an 20 eye (see letter H) just fitted to the point of the hook (see letter I) shuts down over the point of the hook upon any draft being applied to the chain, thereby strengthening the hook preventing it from catching, 25 unhooking, and injuring cattle.

What I claim as my invention and desire to secure by Letters Patent is—

The "iron guard" and the manner of attaching it to the hook.

WILLIS STRAW.

In presence of—

JOHN FARR,

WILLIAM J. BELLOWES.
